MUSICAL INSTRUMENT SUPPORT

Filed Feb. 19, 1925

FIG. 1

FIG. 2

FIG. 3

FIG. 4

FIG. 5

INVENTOR
AUGUST MORTENSEN

BY
Gunter W. Wigand
ATTORNEY

UNITED STATES PATENT OFFICE.

AUGUST MORTENSEN, OF SAN FRANCISCO, CALIFORNIA, ASSIGNOR TO THE "FRISCO" MFG. CO. INC., OF SAN FRANCISCO, CALIFORNIA.

MUSICAL-INSTRUMENT SUPPORT.

Application filed February 19, 1925. Serial No. 10,332.

To all whom it may concern:

Be it known that I, AUGUST MORTENSEN, a citizen of the United States, residing at 244 Eddy Street, San Francisco, in the 5 county of San Francisco and State of California, have invented certain new and useful Improvements in Musical-Instrument Supports, of which the following is a specification.

10 This invention relates to supports or holding devices for musical instruments of various kinds and classes and particularly to large brass instruments, as for example Sousaphones.

15 The object of this invention is to provide a support or holder of this class, combined with means for adjustably supporting an instrument in connection therewith and for moving said instrument into a position to

20 facilitate the playing or operation thereof by a musician, whereby the operator is relieved of the laborious work of holding and supporting such instrument in the operation of playing the same.

25 A further object being to provide a support or holder of the class specified which is composed of a plurality of movable and adjustably connected parts, whereby a complete device may be adjusted into an operative 30 position and held secure in such position.

By the use of this device an operator is 35 enabled to swing his instrument into an inoperative position while seated near this support or holder in substantially a horizontal plane, and is enabled to obtain a rapid replacement of his instrument into an operative position when occasion demands.

Another object of this invention is to 40 provide a support of this sort which may be inexpensively formed from standard metal tubing, and which has an upright member and connecting members of like form, also to provide such supports with 45 improved locking or securing means between the upright member and connecting members, which when released, will permit the support to be easily adjusted to fit different sizes of instruments.

50 The invention is fully disclosed in the following specification, of which the accompanying drawing forms a part, in which separate parts of my improvement are designated by suitable reference characters 55 in each of the views, and in which:

Fig. 1 is a vertical longitudinal side view of my improved support and holding device in an inoperative position and diagrammatically illustrating the method of its use;

Fig. 2 a vertical longitudinal front view 60 of my improved support and holding device in an operative position and diagrammatically illustrating the method of its use by an operator;

Fig. 3 a plan view of part of the construction on an enlarged scale on the line A—A of Fig. 1;

Fig. 4 a detail view of the construction of one of the instrument supporting means; 70

Fig. 5 a detail horizontal view on the line B—B of Fig. 1, illustrating the curvature of another instrument supporting means.

The base 1 is preferably secured to a base 75 board 2, of sufficient size to also accommodate a suitable chair for use by the operator, the chair is intended to be placed directly in front of said base 1, and when so placed, will incidentally prevent any tilting movement of the device. Secured within the base 1 is a tubular standard member 3. An upright member 4 is movably mounted in the tubular standard 3 and is adapted to be adjusted vertically within said tubular 80 standard 3 and being secured in different positions of vertical adjustment by a collar 5, provided with a set-screw 6 which is adapted to engage and hold the collar 5 in position on the upright member 4. The collar 5 is intended to seat upon the upper end of the tubular standard member 3 and revolving thereon as will hereinafter be described.

The horizontally disposed supporting 95 member 7, is curved in an outwardly direction, as shown in detail in Fig. 5, and is provided at one end with a collar 8 which adapts it to be adjustably mounted on the upright member 4 and said collar is provided with a set-screw 9 which is adapted to engage and hold said supporting member 7 in position on said upright member 4.

This method of constructing the said outwardly directed curved supporting member, 105 provides the necessary space needed to permit an operator to be seated between the upright member of the device and the instrument placed thereon without any bodily interference to, or by the operator, as illus- 110

trated diagrammatically in Fig. 2. Secured to the opposite end of said curved supporting member 7, is a collar 10 provided with a set-screw 11. An instrument supporting element, comprising an upwardly directed curved member 12, centrally disposed on this member 12 is a downwardly extending pivot 13 securely attached thereto. The said curved member 12 being pivotally mounted 10 within said collar 10 and adapted to be held and secured therein, in suitable adjustment by means of the set-screw 11. The outer ends of the curved member 12, as at 14 and 15 respectively, are provided with oppositely disposed and upwardly directed curved projecting members 16 provided with felt facings 17. The curvatures of said member 12, and of its projecting members 16, conform very closely to the curvature of the 20 instrument tubing. It being intended to support an instrument therein as illustrated in Figs. 1 and 2. A strap 18 is provided to secure the instrument within this supporting element as shown in Fig. 2.

25 The horizontally disposed bar member 19 is provided at one end with a collar 20 which adapts it to be adjustably mounted on the upright member 4 and is provided with a set-screw 21 which is adapted to engage and 30 hold said bar member 19 in position on said upright member 4. Secured to the opposite end of the bar member is a collar 22 provided with a set-screw 23. The horizontally disposed arm 24, being at one end, as at 25, bent in a downwardly direction to form a pivot, is pivotally mounted within said collar 22, and adapted to be held secure therein, in an adjusted position by means of the 35 said set-screw 23.

40 To the opposite end of the arm 24 is secured a second instrument supporting element, comprising a downwardly directed inverted U shaped member 26, provided with outwardly directed curved end members 27 provided with felt facings 28. The curvature of the members 26 and 27 conforms very closely to the outer contour of the instrument at its point of contact with the said second supporting element, as more 45 clearly illustrated in Fig. 1. A band of suitable webbing is provided, to surround the instrument and to hold it secured against the said supporting element.

50 The use of my improved instrument support or holding device will be readily understood from the foregoing description when taken in connection with the accompanying drawing and the following statement.

55 The support or holding device, with an instrument placed thereon, is normally in the inoperative position shown in Fig. 1 when not in use. In setting the device up for use, the standard upright member 4 is adjusted to the desired height by means of 60 the collar 5. The rounded lower part of the

instrument is then placed into the curved supporting element and secured thereto by means of the strap 18. The upper part of the instrument is then placed against the inverted U shaped member 26 and secured 70 thereto in a similar manner. The inclination of the instrument desired to the vertical line, as shown in Fig. 1, is obtained by suitable adjustments effected by means of the set-screws 21 on collar 20 and 23 on collar 22 respectively.

It may be apparent by now that my improved supporting device may be swung in substantially a horizontal plane, toward or away from the operator or musician while seated, as may be desired, without disturbing the location of its base member 1. The upright member 4 being held in an adjusted vertical position by the collar 5, revolving within the tubular fixed standard 3, on and with the collar 5. The operator or musician, preferably seated on a chair placed in front of the base 1, upon the base board 2, will only need, in order to place his instrument into an operative position, to draw or turn the device including the instrument towards him and by slightly bending forward place the tubing of the instrument about his body, as illustrated diagrammatically in Fig. 2. A musician may then sit in juxtaposition to the support or holding device with the mouthpiece of the Sousaphone in convenient position relative to the mouth of the operator to facilitate the operation or playing of the instrument, and my improved device will eliminate the necessity of the operator holding or supporting the instrument while playing the same.

It has heretofore been the custom to place 105 this instrument over a shoulder of the operator or musician for supporting the same while playing such instrument, this method of suspending the instrument does entirely support the weight thereof, and as instruments of this class are of considerable 110 weight, it is a very tiresome procedure. By using one of my improved supporting devices, however, the operator or musician is taxed in no way in the support of such instrument.

115 It will be understood that while I have shown a specific use of my improved device, that I am not necessarily limited to this use nor am I necessarily limited to the specific construction of the support herein shown and described, and various changes 120 therein and modifications thereof may be made, within the scope of the appended claims, without departing from the spirit 125 of my invention or sacrificing its advantages.

Having fully described my invention, what I claim as new and desire to secure by Letters Patent is:—

130 1. A device of the class described, com-

prising a base member, a tubular standard secured upon said base member, said standard provided with a vertically adjustable member, a horizontally disposed curved supporting member mounted on said vertically adjustable member, means for holding said curved supporting member in different positions of adjustment, a curved instrument supporting element pivotally mounted on said curved supporting member, a horizontally disposed bar member mounted on said vertically adjustable member above the said horizontally disposed curved supporting member and spaced therefrom, means for securing the bar member in different positions against movement, a horizontally disposed arm part pivotally supported by said bar member, said arm part provided with instrument supporting means, said instrument supporting means cooperating with the aforementioned curved instrument supporting element to support an instrument, and operative means whereby the vertically adjustable member including the operating instrument supporting means connected thereto may be swung in substantially a horizontal plane.

2. In a device of the class described, comprising a base member, a tubular standard secured to said base member, said standard provided with a movably mounted upright member, means for securing said movable

upright member in different positions of vertical adjustment, a horizontally disposed, outwardly directed curved supporting member adjustably mounted on said upright member, a collar provided at the outer end of said curved supporting member, an upwardly directed curved instrument supporting member provided with a pivot, pivotally supported within said collar, said upwardly curved instrument supporting member provided with oppositely disposed, upwardly directed projections, a horizontally disposed bar member adjustably mounted on said upright member over and above the said curved supporting member and spaced therefrom, a horizontally disposed arm part pivotally supported by said bar member, means for securing said bar member and said arm part in different position of adjustments, an inverted U shaped instrument supporting element secured to the outer end of said arm part, said inverted U shaped supporting element operatively cooperating with the aforementioned upwardly curved instrument supporting member, in the joint support of an instrument, and operative means whereby the instrument supporting device may be rotated in a horizontal plane.

In testimony whereof I have affixed my signature.

AUGUST MORTENSEN.
